UNITED STATES PATENT OFFICE.

WILLIAM H. LEGATE, OF HARTFORD, CONNECTICUT.

RADIATOR.

1,232,339.

Specification of Letters Patent. Patented July 3, 1917.

Application filed November 8, 1915. Serial No. 60,220.

To all whom it may concern:

Be it known that I, WILLIAM H. LEGATE, a citizen of the United States, residing at Hartford, in the county of Hartford and

5 State of Connecticut, have invented certain new and useful Improvements in Radiators, of which the following is a specification.

This invention relates to radiators. A 10 radiator involving my invention is comparatively light, yet possesses unusual strength. It is simple in construction, consisting practically of merely three parts. It can be easily taken apart for repairs or other purposes, 15 water or its equivalent can freely circulate longitudinally and laterally of the body and can uniformly reach all the parts thereof, said body being of such construction as to permit thorough circulation of air therethrough to aid in maintaining the 20 water cool or to perform some other equivalent office. In addition to this the radiating surface is of considerable extent.

The device possesses other features of advantage and novelty which with the foregoing will be stated at length in the following description wherein I will set forth in detail that form of embodiment of the invention which I have selected for illustration 25 in the drawings accompanying and forming part of the present specification. I do not limit myself to this particular disclosure; I may depart therefrom in several respects within the scope of the invention 30 defined by the claims following said description.

Referring to said drawings:

Figure 1 is a perspective view of a radiator involving my invention as viewed from 35 the inside or back thereof.

Fig. 2 is a front elevation of one side of said radiator.

Fig. 3 is a vertical sectional view of the same.

Fig. 4 is a perspective view of a mold.

Fig. 5 is a detail with parts broken away of a portion of a core.

Fig. 6 is a perspective view of a tubular member showing a way of removing the core 40 therefrom.

Fig. 7 is a sectional elevation of a part of the body of the radiator with the incased core.

Fig. 8 is a sectional view of a portion of 45 the body of the radiator, and,

Fig. 9 is a similar view showing more of

the body, the interior skin or coating not being shown in Fig. 9, but appearing in Fig. 8 for the reason that the latter is on a larger scale than the former.

Like characters refer to like parts throughout the several views, which it will be noted are on different scales.

The present case is a division of my application for patent for method of making 60 radiators, filed May 27, 1915, Serial No. 30,756. The drawings constituting a part of the present application are, as will be understood, duplicates of those forming part of my prior application which as will be 65 obvious discloses one method of several by which a radiator involving my invention can be obtained. In describing the article I will necessarily refer to a method by which 70 the article can be made.

A radiator involving my invention can be employed with utility in widely-different connections, although it is of particular advantage when used in conjunction with or forming part of the equipment of an automobile, providing as will be understood, the necessary water to keep the engine in a relatively-cool condition. The radiator includes a body of grid-like tubular construction and a crown or head pan and a 80 settling or base pan suitably associated together as will hereinafter appear. The "body" as I have termed it, may be and preferably is made through the intervention of a core of some suitable material such as a lead composition which can be easily 85 fused, for instance at a temperature of 202 degrees Fahrenheit. This body has deposited upon it for instance, electrolytically, a metal which may be either copper or brass, 90 the former being quite advantageous. After the metal is deposited on the core, the core is removed, for instance by heat, leaving the grid-like tubular body, and when a lead composition is provided the lead will coat 95 the interior of the tubular like body with a protective skin. With the foregoing general observations I will now describe more 100 in detail what is illustrated in the annexed drawings.

Initially or at some primary stage in the manufacture of the radiator I utilize a grid-like member which is of such character as to be subsequently removed from an integral or one-piece body formed on it. If 110 the external body be of copper, for instance, the interior member would preferably be

fusible. For example the grid-like core can advantageously consist of some lead composition which will fuse as already noted at about 202 degrees Fahrenheit. In Fig. 4 I have shown a mold 2 which is made of some suitable material, bronze answering satisfactorily in this respect. The sections of the mold have longitudinally extending channels 3 and transversely extending channels 4 intersecting the longitudinally extending channels, the channels in the mold sections mating to produce passages fully circular in cross section. From the outside channels in the body section of the mold the bores 5 depend, these bores 5 being fully circular in cross section. The mold has the gate 6 into which the metal to form a grid is poured. When the sections of the mold are closed together molten metal is poured into the mold by way of the gate 6, and it fills the space so as to produce a grid such as that denoted in a general way by 7. The mold and the grid therein have been shown of comparatively small size, this for economy in space and simplicity of illustration. It is a matter of fact, however, that there may be any number of longitudinally extending and any number of transversely extending bars in a grid as 7. In Fig. 4 the upper section of the mold is swung up so that the grid 7 can be removed therefrom if cool. Before forming the body of the radiator, the fin 8 left by casting is removed from the grid 7. It will be clear that said grid comprises a number of longitudinally extending and a number of transversely extending bars or rods, and although these are circular in cross section, it is not necessary that they be made in such shape, but such form is advantageous, in that no angles are presented in the body of the radiator in the length of the tubes thereof. In addition to the longitudinally extending and transversely extending rods or bars of the grid 7 there are projections as 9. As represented these projections 9 extend from the side bars of the grid.

After the formation of a grid it is brought opposite a mating grid as shown for example in Fig. 7 with the flat ends of the projections 9 into abutment as shown on the left in Fig. 5. When this is accomplished the projections are soldered or otherwise suitably united as shown on the right in Fig. 5 so as to produce a duplex grid. As a matter of fact there may be any number of these fusible grids connected together. The connected grids are then coated with the necessary metal which is to form the tubular body of the radiator, and copper or brass answer satisfactorily in this respect, copper in fact being preferable. After the two grids 7 have been united, or after the sections of the fusible core have been connected together as it might otherwise be put, the

core is in readiness to be coated, for example by being immersed in a hot copper sulfate solution, copper being electrolytically deposited upon the core to the requisite thickness, for illustration somewhere between twenty to forty thousandths of an inch thick. After the core is plated, it is taken from the bath and cleaned, subsequent to which it is put in an oven and subjected to heat of approximately 202 degrees Fahrenheit, which melts the core, the core in molten condition running from the tubular body as shown in Fig. 6 which might be assumed to represent one of the longitudinally extending tubes 10 of the radiator body denoted in a general way by 11. There will be two series of such longitudinally or vertically extending tubes 10, one at the front and the other at the back of said body, the side tubes of the two series being united by connecting tubes 12. The longitudinally or vertically extending tubes 10 are connected by transverse tubes 13. As will be inferred there may be any desired number of these longitudinally extending tubes 10 and 90 the same observation applies with respect to the transversely or laterally disposed tubes 13. In like manner it is not essential that the connecting tubes 12 as I have termed them connect the side tubes of the front and rear series of tubes, although this construction is desirable. The radiator body 11, as will be clear, comprises a front tubular grid and a rear tubular grid in communication with each other by way of connecting tubes, all the tubes in fact being in communication with each other to provide for the proper circulation of the cooling liquid which when the radiator is used on an automobile would be water under ordinary circumstances. While the longitudinally and transversely extending and connecting tubes of the body 11 are disposed at right angles to each other, this may not always be necessary. It will be clear that all the tubes when a fusible core is utilized in the formation of said body are interiorly coated with the fusible material, sufficient of the material remaining for this purpose. Fig. 9 represents a portion of the body 11. The tubes are not shown coated, the coating being omitted on account of the smallness of scale of this particular view. Fig. 8 is on a larger scale and shows the coating in the tubes of the body. The interiorly coated shell-like or hollow body is now in readiness for assemblage with the remaining parts of the radiator. In addition to the body 11, said radiator comprises a base or settling tank or pan 14 and a crown tank or pan 15. The upper or head tank is provided with a discharge nipple or tube 16 adapted to be connected in some suitable way with the water space of the engine, this water space delivering in turn (through suitable connec- 130

tions with the nipple or tube 17), the water or other liquid after it has exercised its function. This nipple or tube 17 is connected with the base or settling tank 14. 5 The upper tank 15 is provided with the removable screw-threaded cap 18 such as is commonly used in automobile radiators, and in addition is provided with the customary overflow pipe 19. The lower pan 14 and 10 upper pan 15 are usually and preferably cast integral, their inner walls being perforated near the front and rear thereof to receive the upper and lower terminals of the longitudinally extending rods 10 of the 15 reticulated or foraminous hollow or tubular body 11, said terminals being soldered or welded or otherwise secured in a liquid-tight manner in the respective perforations. Preferably formed integrally with the lower 20 pan 14 are the side members 20 of practically duplicate construction and which present in fact the sides of the radiator. The 25 ends of the upper pan or tank 15 are rabbeted or channeled as at 21 to receive the upper ends of the side members 20, said side members being fastened to the upper pan in any desirable manner as by screws 22 tapped into the end portions of said upper pan 15. The heads of the screws are 30 countersunk in said side members 20 and after the screws have been driven home solder 23 will be flowed into the slots of the screws. The side members 20 have as shown inwardly extending flanges, the upper ends 35 of which abut against the bottom of the pan 15 to aid in upholding the pan, the flanges overlying the front of the radiator body 11 at the sides thereof. The upper 40 ends of the side members 20 it will be noticed, abut against the tops of the rabbets 21 to

further aid in upholding the pan 15. It will be clear, therefore, that the flanges 24 are not coextensive with the side members 20 but extend short of the upper ends thereof. 45

It should be noted that the ends of the transversely extending tubes of the grid-like body of the radiator abut against the sides 20 and that these sides actually close in a liquid tight manner, the opposite open 50 ends of the transversely extending tubes of said grid-like body.

What I claim is:

1. A radiator comprising an integral body having longitudinally and transversely disposed connected and communicating tubes, 55 tanks in which the longitudinally extending tubes are fitted in a liquid tight manner, and side pieces between the tanks, the ends of the transverse tubes being open and said side pieces closing the outer ends of the transversely extending tubes.

2. A radiator comprising an integral body having longitudinally and transversely disposed tubes in two series and also having 65 tubes extending from front to rear and connecting the two series of tubes, and tanks having openings in which the two series of longitudinally extending tubes are fitted in a liquid-tight manner, the ends of the 70 transversely disposed tubes being open, and side pieces connecting the two tanks and closing the open ends of the transversely disposed tubes.

In testimony whereof I affix my signature in presence of two witnesses.

WILLIAM H. LEGATE.
